US00D829487S

(12) **United States Design Patent** (10) Patent No.: **US D829,487 S**
(45) Date of Patent: **** Oct. 2, 2018**

(54) **COOKING APPARATUS**

- (71) Applicant: **Tristar Products, Inc.**, Fairfield, NJ (US)
- (72) Inventors: **Keith Mirchandani**, Fairfield, NJ (US); **Paul McGrath**, Flanders, NJ (US); **James Mitrik**, Long Pond, PA (US); **Alejandro G. Lozano**, Guttenberg, NJ (US)
- (73) Assignee: **Tristar Products, Inc.**, Fairfield, NJ (US)
- (**) Term: **15 Years**
- (21) Appl. No.: **29/596,310**
- (22) Filed: **Mar. 7, 2017**

Related U.S. Application Data

- (63) Continuation-in-part of application No. 29/580,364, filed on Oct. 7, 2016, and a continuation-in-part of application No. 29/595,955, filed on Mar. 3, 2017.

CLAIM

The ornamental design for a cooking apparatus, as shown and described.

DESCRIPTION

FIG. 1 is a front perspective view of a cooking apparatus in accordance with the subject disclosure.

FIG. 2 is top view of the cooking apparatus of FIG. 1.

FIG. 3 is a bottom view of the cooking apparatus of FIG. 1.

FIG. 4 is a front view of the cooking apparatus of FIG. 1.

FIG. 5 is a rear view of the cooking apparatus of FIG. 1.

FIG. 6 is a top perspective view of the cooking apparatus of FIG. 1.

FIG. 7 is a bottom perspective view of the cooking apparatus of FIG. 1.

FIG. 8 is a right side view of the cooking apparatus of FIG. 1; and,

FIG. 9 is a left side view of the cooking apparatus of FIG. 1.
